UNITED STATES PATENT OFFICE

THOMAS EDWIN ANDREW AND MELON LANGSTRETH, OF ROCHDALE, ENGLAND, AS-SIGNORS TO DUNLOP COTTON MILLS LIMITED, OF LONDON, ENGLAND, A CORPORATION OF GREAT BRITAIN

MACHINE FOR SPINNING, DOUBLING, TWISTING, AND THE LIKE YARNS, FIBERS, AND THE LIKE

Application filed November 18, 1927, Serial No. 234,232, and in Great Britain November 22, 1926.

This invention relates to spinning, twisting, doubling and the like machines of the kind, hereinafter called double twist machines adapted to impart two twists to the 5 roving, yarn, thread or the like, hereinafter called the yarn, at every single revolution of the spindle.

In this class of machines the yarn in transit during treatment is formed into a loop held 10 relatively fast at points adjacent the wind-off spool and the take-up spool respectively and the loop is rotated at its closed end so that one leg of the said loop rotates about the other. Thus two twists are imparted to the 15 yarn, one between each respective relatively fast point and the rotary point.

Hereinafter the terms "bobbin" and "reel" occur frequently and in order that the significance thereof may be appreciated the use 20 of the said terms is explained in the following paragraph.

In ring and traveller- and also in flier machines, the twisted yarn is invariably wound onto the spool associated with those devices. 25 Now in this respect there are two main classes of double twist machine, the same being (a) those wherein the twisted yarn is wound onto the spool associated with the twisting devices—the same sequence as in ring and traveller machines and (b) those wherein the 30 said sequence is reversed—the twisting devices being associated with the spool of untwisted yarn. This invention has particular reference to the latter class and hereinafter 35 the term "bobbin" is used in connection with the spool carrying the untwisted yarn and the term "reel" with spool whereon the twisted yarn is wound.

This invention relates mainly, but not 40 wholly as hereinafter indicated, to improvements in the type of this class (b) of double twist machines wherein the yarn is led from the bobbin, through the centres respectively of the spool thereof and the spindle upon 45 which it is stationarily mounted, out at the side of the said spindle and thence to the reel. Of the points referred to in the second paragraph hereof the rotary point occurs where the 50 yarn leaves the spindle while the two relatively fast points occur, one between the said

rotary point and the bobbin, and the other between the said rotary point and the reel.

Many designs for such machines have hitherto been devised but all such machines within our knowledge have invariably utilized, 55 mainly for the purpose of guiding the yarn from the bobbin to the relatively fast point there-adjacent, some device, extraneous to the said bobbin such as a structure disposed substantially parallel to the axis of the said bobbin; and various tensioning devices have been 60 associated therewith.

Proposed schemes such as these have been known to the trade for many years but their complete lack of success in practical application has probably been due to the cumbersome 65 and complicated nature of their construction.

It is an object of this invention to simplify the construction adjacent the bobbin and to increase the efficiency thereof by providing 70 new and improved means whereby the yarn may be guided to the first relatively fast point, which means are adapted to obviate the necessity for such a structure as that referred to. 75

According to our invention, therefore, we provide a new and improved guiding and tensioning device which is preferably adapted to be housed rigidly within the bore of the spool of the bobbin.

It will be apparent that such a device is admirably suited to eliminate completely the old cumbersome structure—by obviating its necessity as a device essentially for guiding and tensioning—but the said invention is applicable in a lesser degree as an improvement on and in association with machines as hitherto composed, the said structure then being adapted to function as a support for the said device and, as hitherto, as means to weight 80 the bobbin against rotation. 85

It will be apparent that when our invention is applied in its preferred form it is necessary to provide means independent thereof whereby the rotation of the bobbin is prevented; and suitable means are the subject of our co-pending application, Serial No. 234,233, filed Nov. 18, 1927. 95

Such means have usually been associated as herein before indicated with the guiding 100

of in zig-zags rather than in convolutions—the aforesaid facility for varying the tension being, it should be noted, maintained—said tension being dictated of course by the number of zig-zags occasioned. Such zig-zags 5 may be obtained, for example, by causing the yarn to pass through offset spaces or equivalent means on the tubular member through which the yarn passes.

10 Such a zig-zag arrangement may be combined with a spring control of the tension as illustrated in Fig. 3 of the accompanying drawing.

As there exemplified the shank 5 has a slat-like extension 19 upon which is slidably mounted a similar slat 20 anchored to the shank 5 by a spring 21 adapted to accommodate or neutralize difference in the tension in the yarn, said tension being occasioned by the 20 zig-zagging of the yarn between the two said slats as shown in the drawings.

Or again, regarding the mounting means, it will be apparent for instance that, as exemplified in Fig. 4, the arrangement shown 25 in Fig. 2 may be reversed—the outer races of the bearing 11 then being fast with the spindle 13 and the inner races carrying the support for the bobbin spool. Or again, the said spool may have an extension adapted to 30 fit into the bore of the inner races of the bearings. And further, said inner races may be joined by a tubular sleeve.

It will however be apparent in general that the mounting may be arranged in any convenient manner, such for instance as is indicated 35 in our aforesaid co-pending application, Serial No. 234,233, filed November 18, 1927. Or again for instance arrangements similar to those therein described or claimed may be 40 utilized less the ball or similar bearings wherein these said arrangements are characterized; it being apparent that we do not confine ourselves to the utilization of such anti-friction bearings although, of course, their 45 use is most desirable.

Again, as exemplified by the disposition of the weight 14 in Fig. 4, it will be apparent that provision may be made to balance or partly to balance the overhanging weight of 50 the bobbin and its association parts.

Again while the description is confined to a horizontal or slightly inclined disposition it will be readily understood that the spindle 55 may be disposed substantially vertically—only slightly inclined to allow the weighing to function—the mounting of course being suitably modified to meet the new condition.

Again it will be apparent that we do not limit ourselves to only one package of yarn 60 as for instance we may use two or more whereof the respective yarns preferably would be themselves twisted and cabled or twisted together.

In conclusion while we have confined the 65 description to machines wherein the yarn is

led through the center of the spindle, a bobbin mounted and provided with a guiding and tensioning device according to this invention may also be utilized in the other of the two main types of machines hereinbefore referred to. That is, the type where-in the bobbin is mounted in a quadrilateral frame or closed flier, occasionally having flexible sides, and having bearing points at each end, the yarn being led from the bobbin via a guide, through one of the bearing points, out at the side thereof, along one arm of the frame, through the side of the other bearing point, into the bore thereof and thence to the take-up reel. Of the points referred to in the second paragraph hereof, the rotary point occurs at the bearing points while the relatively fast points occur, one between the bobbin and the first bearing point and the other between the reel and the last bearing point.

Having now particularly described and ascertained the nature of our said invention and in what manner the same is to be performed, we declare that what we claim is—

1. An apparatus of the type described which comprises a rotating drive spindle and a non-rotating bobbin removably mounted on the free end of said spindle, said spindle and bobbin having a central yarn passage therethrough and a tubular member removably mounted on the free end of said bobbin and said tubular member having openings through which said yarn may be threaded to create tension as it is drawn therethrough.

2. An apparatus of the type described which comprises a rotating drive spindle and a non-rotating bobbin removably mounted on the free end of said spindle, said spindle and bobbin having a central yarn passage therethrough, a tension member mounted on the free end of said bobbin, said tension member having unaligned openings through which yarn may be threaded with changing direction to create tension as it is drawn through said passage.

In witness whereof, we have hereunto signed our names.

THOMAS EDWIN ANDREW.
MELON LANGSTRETH.
